UNITED STATES PATENT OFFICE.

WILLIAM S. HULL, OF SHEFFIELD, ALABAMA, AND JAMES C. ANDERSON, OF CHARLESTON, NORTH CAROLINA.

ELECTRIC RAILWAY SWITCH AND ALARM.

SPECIFICATION forming part of Letters Patent No. 399,331, dated March 12, 1889.

Application filed May 21, 1888. Serial No. 274,526. (No model.)

To all whom it may concern:

Be it known that we, WILLIAM S. HULL, residing at Sheffield, in the county of Colbert, State of Alabama, and JAMES C. ANDERSON, residing at Charleston, in the county of Swain, State of North Carolina, both citizens of the United States, have invented certain new and useful Improvements in Electric Railway Switches and Alarms, of which the following is a specification, reference being had therein to the accompanying drawings.

This invention has relation to railway switches and alarms.

Among the objects in view are to provide an electrical and mechanical construction which will not only serve the purpose of indicating any displacement of the switches, but which shall also be adapted for conveying messages back and forth between the office or other place and the switch-stand; furthermore, to prevent so far as possible mistakes upon the part of the switchman in the manner of using the apparatus involved.

Other objects and advantages of the invention will hereinafter appear, and the novel features thereof will be particularly pointed out in the claims.

Referring to the drawings, Figure 1 is a side elevation, Fig. 2 a transverse vertical section, Fig. 3 a transverse horizontal section, and Fig. 5 a vertical horizontal section, of a switch-box and its contained mechanism constructed in accordance with our invention. Fig. 4 is an elevation of the lock detached, showing its interior construction. Figs. 6 and 7 are details of the switch bar or rod. Fig. 8 is a vertical section, and Fig. 9 a horizontal section, of the alarm mechanism located at the main office or other point.

Similar numerals of reference indicate similar parts in all the figures of the drawings.

1 represents a cast-metal or other case, which is adapted by bolts 2 to be secured to the switch head-block. The cover of the case 3 is secured by bolts 4 and provided with a boss, 5, through which a bearing is formed for the switch-shaft 6, the lower end of said shaft being seated in a bearing, 7, formed in the bottom of the box. The hub 5 is provided with notches or slots 8 for the reception of a locking-dog, 9, pivoted at 10 to a collar, 11, secured to the switch-mast by a set-screw, bolt, or other suitable device, 12. The num-

ber of notches 8 formed in the hub is made to conform to the number of throws which the switch is designed to have. In this instance it is provided with two notches or slots, as for the purpose of illustrating our invention a two-throw switch is sufficient, although it is stated that the same may by the exercise of mechanical skill be adapted to switches having more throws.

Within the case, and rigidly secured to the switch-mast 6, is a half-pinion, 13. In case the invention is applied to a switch having more than two throws the teeth of the pinion may extend entirely around the same, and any geared rack-bar or switch-bar co-operating therewith would be properly proportioned thereto. So, also, in giving additional reciprocation to a switch-bar the size of the pinion may be increased.

Extending longitudinally in the case, and provided with teeth adapted to mesh with the pinion 13, is a switch bar or rod, 14, formed in sections and pivoted together, as at 15, within the case; or it may be entirely without the same. The bar 14 is provided with a recess, 16, (see Fig. 6,) for the reception of the bolt 17 of a lock, 18, which is arranged within the case and adapted to be reached by a key passing through a hole, 19, formed in the wall of the case in proximity to the lock, to which wall the lock is secured. Suitable guide-plates, 20, for the bar 14 are formed within the case, upon which the bar reciprocates, and by which it is held in mesh with the pinion.

A washer, 21, may be arranged at the end of the bar and about that portion thereof pivotally connected therewith, for the purpose of preventing the entrance of dirt, dust, and moisture. The switch-mast is provided with the usual operating hand-wheel, 22, and lamp and signals, the two latter not being shown.

As thus far described, it is clear that a rotation of the switch-mast will cause a reciprocation of the switch-bar, and that the recess 16 therein will be immediately above the bolt of the lock 18, so that the same may be secured against further reciprocation. The parts occupy this position when the main line is complete or closed. When the side track is connected with the main line or the switch open, the end of the bar 14 abuts against a solid portion, 23, of the wall of the case.

One of the principles of the invention is secured by constructing the lock in such a manner that the key can be removed therefrom only when the bolt 17 is projected from the lock-case, and therefore the switch is not in condition to be operated by unauthorized or evil-disposed persons. This object is accomplished in the following manner: The bolt 17 is provided with a key-blade-receiving slot, 24, and with a detent-recess, 25, at opposite edges of the bolt. The detent 26 is pivoted to the wall of the lock-case, as at 27, and has an arm, 28, (see dotted lines, Fig. 4,) which projects beneath the bar 17, between it and the case, and across the path of the key-blade. When the key is inserted in the hole 29 of the lock-case and turned over to the left, (taking the parts as illustrated in Fig. 4,) it first enters the slot 24, which, when the bolt 20 is thrown out of the case, is in the position shown by dotted lines, comes in contact with the arm 28 of the detent, lifting the end 26 thereof out of the recess 25, and then comes in contact with the walls of the slot 24 and 25 brings the bolt into the case. The parts are now in the position shown in full lines in Fig. 4, and it is apparent that the key cannot be withdrawn, as its blade lies against a solid portion of the lock-case, and that it is necessary to turn it into alignment with the key-hole in order to withdraw it, whereby in such return movement the switch will become locked. Furthermore, the locking of the switch for the purpose of removing the key 30 cannot be accomplished except the recess 16 be in position above the lock, and therefore except the main line be closed.

In connection with the mechanical features above described we employ an electrical system to attain further objects of our invention. The bar 14 is provided with a binding-post, 31, having a suitable contact-point, 32, and from the post 31 an electrical conductor extends to the ground. To the case and insulated therefrom is secured a bracket, 34, carrying a contact-point, 35, which is in the path of the contact-point 32 of the binding-post 31. Contact-point 35 is connected by a conductor, 36, passing insulated through the case to a binding-post, 37, which is electrically connected with an alarm at the main or other office or point.

As thus far described, it will be seen that when the main line is closed and everything is safe an electrical circuit will be closed, and this may be utilized at the main office or other point to control any suitable signal to indicate "safety," so that a displacement of the switch, the bar, the bolt, or the lock, or, in fact, any defect in the electrical circuit itself, would be announced at the office or other point. This electrical connection is applicable to any switch, and is not confined to the one described.

65 In addition to the capabilities of the apparatus to automatically indicate at the main or other office its condition, provision is made

whereby communication with the main office by the switchman can be had.

It is evident that by a preconcerted arrangement a repetition of throwing the switch-bar, and consequently throwing the danger-signal into and out of sight, may be the means of conveying information from the switchman to the office, this being one of the principal features of the invention. This object is, however, more efficiently attained by providing the lock-case 18 with an insulated binding-post, 37, having a contact-point, 38, projecting into the path of a contact-point, 39, mounted on and moving with the bolt 17 and electrically connected to an insulated binding-post, 40, and to alarm visual or audible signals at the main office or other point by the line 41, the binding-post 37 being electrically connected by the line 42 with the ground. Now when the bolt is thrown from the lock by the key 30 contact is made between the points 38 and 39, and the alarm or indicating mechanism at the main office or other point may be constructed to announce that fact, and by a preconcerted arrangement of signals a repetition of acts of locking and unlocking with the key 30 serves, as a manner both convenient and simple, for conveying intelligence from the switchman to the main or other office.

In Figs. 8 and 9 are illustrated one form of signals, visible and audible, which may be employed with the mechanism hereinbefore described. Fig. 8 is a vertical longitudinal section, and Fig. 9 a vertical transverse section on the line *x* *x* of Fig. 8.

In a suitable case, 43, or in any other suitable manner for suspension, there is mounted upon adjustable pivot-bearing pins 45 a swinging armature, 46, carrying a plate, 47, marked "Danger." The armature 46 is connected by a spring, 48, with a wall of the case, the tendency of the spring being to draw the armature to such position that its plate will stand opposite a sight-opening in the wall of the case, as indicated by dotted lines, 49, Fig. 8, so that when not otherwise influenced the armature-plate will be in sight. A pair of coils, 50, is mounted upon an inclined partition or plate, 51, secured across one corner of the case, so that the poles of the magnets are presented in a position to influence the armature 46 when a current is flowing through the magnets. At the same side of the armature 46 as that at which the spring 48 is arranged is a contact-point, 52, electrically connected with the magnets 53 of an electrically-operated bell, the other wire of the circuit being connected by a line, 54, with the armature 46, so that an audible signal of "danger" is provided in addition to the visual signal.

Referring now to Figs. 5 and 8, it will be seen that as the binding-post 37 is connected with the binding-post 54 a circuit is established when the switch is turned to close the main line as the contact-points 32 and 35 com-

plete the circuit with the magnets 50, which attracts the armature 46 and draws it against the tension of the spring 48, so as to throw the danger-signal out of sight. At the same time a current passes by a line, 55, independent of circuit 54, to the magnets 53, and an audible signal is given on the bell 56. It is also readily seen that when the line 41, Fig. 4, is connected with the line 57 of the electrical-bell magnet armature 58, which carries the hammer of the bell, is attracted and an audible signal given, and the strokes of the bell may be controlled by the number of oscillations of the key-blade and of the bolt 17, which it operates. The two wires shown near the binding-post 54 lead from the two magnets 50, and said magnets are entirely independent of the bell mechanism, the latter being operated by the circuit connected with the lock, while the former is connected with the circuit on the switch-bar. The wire on the magnet 53, after its exit at 54^a, passes through one of the two wires shown above said magnet, according to the position of the lock at the switch, and consequent position of the danger-signal, and returns through the magnet 53 in such a direction as to increase its power, emerging at 57, as shown.

It is understood that a suitable battery or other source of electricity is properly connected with the apparatus above described. By giving each switch a number and a similar number to the key of its lock and to the alarm or signal case at the main office or other point the locality and identity of the switch and switchman are established, and in case of the imperfect performance of duties—for example, leaving a switch open—the presence of the key in the lock will indicate the person who has been derelict in his duty.

Various modifications and changes within the skill of persons conversant with the construction of switches and electrical apparatus may be made without departing from our invention.

For the purpose of rendering the switch-bar 14 adjustable, and in order that the rails may be maintained in perfect alignment, we form said bar in sections, as before described, the ends of which are screw-threaded and connected by a right and left screw-threaded coupling, 15^x.

Having described our invention and its operation, what we claim is—

1. In a railway-switch, a lock for securing the operating parts in a desired position, having a bolt, 17, bearing a contact-point, and a second contact-point so placed as to touch the first when the bolt is in the locking position, in combination with an electric alarm and a circuit connected therewith and with the two contact-points, substantially as described.

2. The combination, with the switch-bar of a railway-switch, of a case inclosing said bar, and having therein a lock for securing said bar in a desired position, contact-points on

the bolt and case of said lock, and an electric circuit terminating in said points, substantially as described.

3. The combination, with the switch-bar of a railway-switch, of a case inclosing the same and its operating mechanism and carrying an electrical contact-point arranged in a circuit and a companion contact-point mounted on the switch-bar and electrically connected with the ground, substantially as specified.

4. In a railway-switch, a lock for securing the operative parts in a desired position, having a casing, a bolt, 17, bearing a contact-point, and a second contact-point so placed on the inside of said casing as to touch the first contact-point when the bolt is in locking position, in combination with a slot in said casing for the reception of a key, said slot so directed as only to admit of the removal of the key when the bolt is shot, and an electric alarm and circuit connected therewith and with the two contact-points, substantially as described.

5. In combination with a railway-switch, circuit making and breaking devices arranged in circuit with an electrical magnet, a signal-plate carrying a pivoted armature, and an audible alarm connected with said armature, and with a contact-point thereon, and a spring for completing the circuit of the audible signal when the armature is otherwise uninfluenced, substantially as specified.

6. The combination, with the railway-switch, of the case 1, having the cover 2, provided with the boss 5, perforated for a bearing for the switch-mast 6, and having notches 8, the collar 11, the dog 9, the pinion 13, switch-bar 14, and the lock 18, substantially as specified.

7. The combination, with a railway-switch operating-bar and mast, of a case inclosing the bar and having guides for the same, and a lock for securing the bar in a desired position within the case, substantially as specified.

8. The combination, with a railway-switch and its operating-bar, of a case provided with a lock, a detent secured to the case of the lock and adapted to take into a recess formed on the edge of the bolt when the latter is thrown from the case, and a key adapted to throw the detent out of connection with the bolt, and the latter being slotted to retain the key from withdrawal from the lock when the bolt is in an unlocked position, substantially as specified.

In testimony whereof we affix our signatures in presence of two witnesses.

WILLIAM S. HULL.
JAMES C. ANDERSON.
